SIGNAL OR CONTROLLING DEVICE

Frank W. Jackson and Harry M. Nacey,
Chicago, Ill.

Application July 27, 1939, Serial No. 286,781

2 Claims. (Cl. 209—81)

Our invention relates to apparatus particularly designed to be used in connection with a container, tank, boiler, conduit or the like for indicating a condition within the same either level or flowage, or to so control other apparatus as to vary or change or maintain the conditions within the container to a desired extent. Primarily the device is intended to control, i. e. open or close, an electric circuit or plurality of circuits, thereby giving an indication either visible or audible, set off an alarm, or start or stop electrically driven or controlled apparatus, or any and all of them separately, successively or simultaneously.

The invention has among its objects the production of a device of the kind described that is simple, compact, inexpensive, efficient, durable, readily installed and thoroughly dependable.

The invention has particularly as an object the production of an efficient and reliable device of the kind described adapted for use on containers or conduits for fluids, whether liquids or gases or other materials capable of movement or variation, for indicating conditions within the container or conduit or for controlling suitable apparatus to maintain or vary the conditions in the container, conduit or its equivalent in a predetermined or desired manner.

It has as a further object the production of a device which does not require stuffing boxes and packing glands regardless of the nature of the material contained or conveyed, and which employs a minimum number of parts which will not readily become inoperative or get out of order.

Many other objects and advantages of the construction herein set forth will be obvious to those skilled in the art, as will also the numerous possible applications and uses of the device.

To this end our invention consists in the novel construction, arrangement and combination of parts herein shown and described, and more particularly pointed out in the claims.

In the drawing, wherein like reference characters indicate like or corresponding parts:

Fig. 1 is a sectional view through one embodiment of our device showing its application to a tank or conduit;

Fig. 2 is a sectional view taken substantially on line 2—2 of Fig. 1;

Fig. 3 is a sectional view taken substantially on line 3—3 of Fig. 1; and

Fig. 4 is a view similar to Fig. 1 illustrating another embodiment of the invention.

Referring to the drawing, 1 represents a container such as a conduit, a tank, boiler or the

like of the desired size, shape and material for containing fluid such as a liquid or gas or material that may be flowed through or displaced in a container. Associated with the container 1 is a housing consisting of the body part 2, which is shown provided with a closure 3 which may be secured in any suitable manner, as for example by the studs shown, packing ordinarily being positioned between the cover and the flange of the housing. The housing is shown provided with a nipple or tubular portion 4 which is arranged to threadedly or otherwise engage with the flange 1 or its equivalent secured to the wall of the container 1 at the opening 8. The housing forms the chamber 5 which communicates with the interior of the container 1 through the tubular bore or passage 6 in portion 4 of the housing and opening 8.

Arranged within the housing is a tube 9 which is shown secured to the cover 3 at 10 and is open at the end, as indicated at 11, to the exterior of the housing. In the embodiment shown in Fig. 1 the tube 9 is bent back upon itself or U-shaped as indicated at 12, with the free or opposite end 13 brought adjacent the passage 6 and sealed by the plug 14 or in an equivalent manner. The tube, which may be of any suitable material, preferably a material having some resiliency, is thus seen to be anchored at one end, which end is open to the exterior of the housing, with the other end which is closed substantially free to move within the housing. The material used will be such as to resist corrosion.

Arranged within the tube is a rod 15 having one end secured to the plug 14 and extending therefrom through the tube and bent at 15' and thence extending as at 16 out through the opening 11. This rod 15—16 is preferably of flexible spring material. The tube and rod as an assembly may be bent up from straight pieces of stock in a manner familiar to those skilled in the art of bending tubes, or the tube may be formed with a separable end 17 adjacent the bend 12 which may be positioned and secured and sealed after the rod has been positioned. Any equivalent construction may be employed.

In Fig. 1 we have shown an impeller, paddle or vane 18 arranged within the container 1, such device being adapted to be moved or controlled by fluid passing through or moving in the container. In some instances this impeller will be a float, as for example as illustrated in the embodiment shown in Fig. 4, or any other means satisfactory for the purpose. The impeller 18 is

shown secured to a link or arm 19 pivotally secured to the housing by a pin 20 passing through the end of the link and through lugs 4' on the interior of the passage in the part 4. Also arranged within the passage 6 is a link 21 which is pivotally secured at 22 with the arm 19 and at 23 to the plug 14 at the end 13 of the tube. When the impeller 18 is moved up or down in the container its movement is transmitted through arm 19 and link 21 to the tube, and moving the end of the tube 13 in one direction or the other moves the looped end 12 likewise, as well as the contained rod 15—16. As for example, pulling the end of the tube toward the container, as indicated in the dotted lines in Fig. 1, tends to move the upper end of the rod in the same direction, as is indicated in dotted lines.

The movement of the upper end of the rod 16 at the exterior of the housing may be utilized in giving a visible signal, as for example by causing it to move as an indicator in itself or to close or open an electric circuit, as the case may be. As shown in Fig. 1, it is adapted to close the circuit when moved as indicated in the dotted lines, or to break it when moved in the opposite direction. As shown, a contact 24 is arranged on the head 23 at the end of the rod, arranged to cooperate with the contact 25 mounted on the head 26, illustrated as carried from the bracket 27 on the cover 3. The contacts 24 and 25 are shown connected by electrical conductors 28 to a suitable piece of electrical apparatus 29, such as an electric light, a bell or an electric motor or the like which may in turn control a pump, valve or any other piece of apparatus, 30 representing a battery or other source of electrical energy. It will thus be seen that movement of the member 13 will make or break contact between the contacts 24 and 25. While only two contacts are shown, it will be perfectly obvious to those skilled in the art that there may be any number or pairs of contacts so as to control more than one circuit, and that if contacts (not shown) are arranged at the opposite side of the head 23, movement of the head 23 to the left may be utilized to close the circuit similar to movement to the right closing the circuit as illustrated in Fig. 1. The device described is very compact, the bend in the tube and rod gives greater movement than a short single tube, causing considerable movement of the head 23.

In some instances it may be preferred to use a straight tube and rod rather than the loop or U-shaped tube and rod. Such embodiment is illustrated in Fig. 4, in which the operation of the device is the same as that shown in Fig. 1. Referring to Fig. 4, 32 represents a housing provided with a closure 33 and with the elbow 34 connected with the flange 37 arranged on the tank or conduit 31. The housing is chambered as indicated at 35 and communicates with the tank 31 through the passage 36 and opening 38 in the tank or receptacle. Arranged within the housing and carried by the closure 33 to which it is secured at 40, is a tube 39 which is also open at the fixed end as shown at 41. The opposite end of the tube, that is the free end 43, is closed by the plug or closure 44 which tightly seals the same. Arranged within the tube is the rod 45 having its one end secured in the plug 44 and its opposite end 46 projecting from the housing and providing an actuator for one of the electrical contacts, as shown.

We have illustrated in Fig. 4 a float 48 which is

connected by rod 47 with an arm 49 pivotally secured at 50 to the lugs 34' on the interior of the elbow 34. The arm 49 is pivotally secured to a link 51 at points 52 and 53. As the float is raised or lowered, it actuates the lower end of the tube and rod through the connecting mechanism described, moving the upper end 46 of the rod, making or breaking the circuit, as the case may be, or otherwise giving an indication that the float has been moved.

Obviously, in the case of a conduit for indicating or controlling the flow, an impeller 18 or some similar device as an equivalent for 18 may be employed, while in a tank or receptacle, boiler or the like for indicating or controlling the level of the contents, a float 48 or some equivalent would be employed. In other words, the particular device for actuating or controlling the link or arm 19 or arm 49 would depend upon the use of the device.

The device described has practically innumerable applications, either for indicating purposes, for automatically controlling devices, or for determining or maintaining or varying the condition of any fluid or other material within a container regardless of whether the same be a conduit, tank, boiler or the equivalent.

Having thus described our invention, it is obvious that various immaterial modifications may be made in the same without departing from the spirit of our invention; hence we do not wish to be understood as limiting ourselves to the exact form, construction, arrangement and combination of parts herein shown and described, or uses mentioned.

What we claim as new and desire to secure by Letters Patent is:

1. In a device of the kind described, the combination of a container, a housing attached thereto and communicating therewith, a U-shaped flexible tube positioned in said housing, said tube having one end secured to the housing and communicating with the exterior thereof, and closed at the other end, means flexibly connected with the latter end positioned in said container and actuatable by predetermined conditions therein to move the closed end of said tube relative the opposite end thereof, a U-shaped rod positioned in said tube, one end of said rod positioned adjacent the closed end of said tube and secured thereto, the opposite end extending exteriorly the housing, and further means positioned exteriorly the housing responsive to movement of the exterior end of said rod as said tube is flexed for producing a desired result.

2. In a device of the kind described, the combination of a container, a housing attached thereto and communicating therewith, a U-shaped flexible tube positioned in said housing, said tube having one end secured to the housing and communicating with the exterior thereof, and closed at the other end, means flexibly connected with the latter end positioned in said container and actuatable by predetermined conditions therein to move the closed end of said tube relative the opposite end thereof, a U-shaped rod positioned in said tube, one end of said rod positioned adjacent the closed end of said tube and secured thereto, the opposite end extending exteriorly the housing, and a circuit breaker operatively connected to said rod and actuated thereby.
